(57) **CLAIM**

The ornamental design for a flotation device, as shown and described.

DESCRIPTION

FIG. 1 depicts a front perspective view of the flotation device;
FIG. 2 depicts a side elevation view of the flotation device;
FIG. 3 depicts a top plan view of the flotation device;
FIG. 4 depicts a bottom plan view of the flotation device;
FIG. 5 depicts a front elevation view of the flotation device;
and,
FIG. 6 depicts a rear elevation view of the flotation device.
The dashed and dotted lines shown are provided for environmental purposes only and form no part of the claimed design.
